UNITED STATES PATENT OFFICE.

HOWARD O. CARTER, OF DETROIT, MICHIGAN.

MOTOR-CAR.

No. 845,850.

Specification of Letters Patent.

Patented March 5, 1907.

Application filed December 10, 1906. Serial No. 347,218.

To all whom it may concern:

Be it known that I, HOWARD O. CARTER, a citizen of the United States, residing at Detroit, in the county of Wayne and State of Michigan, have invented certain new and useful Improvements in Motor-Cars, of which the following is a specification.

This invention relates to motor-vehicles, and more particularly to a form of automobile in which there are two engines or two sets of engines which may be connected separately to the driving-wheels, or both thrown in, as desired.

The object is to provide a simple well-balanced construction in which injury to an engine or a crank-shaft will not disable the machine.

According to my invention two engines or two sets of engines, preferably disposed vertically, are located at the front of the frame at either side of the longitudinal median line thereof. Each engine or set is equipped with a longitudinal crank-shaft, two intermediate shafts are located in alignment therewith, means is provided for coupling either or both the intermediate shafts with the corresponding crank-shaft, and gearing is provided between the intermediate shafts and a central longitudinal driving-shaft.

In the drawings, Figure 1 is a plan view. Fig. 2 is a side elevation. Fig. 3 is a detail of the clutch-operating foot-levers. Fig. 4 is a detail of one of the clutch devices.

Referring to the drawings, A indicates a suitable frame for the automobile, and B the driving-wheels thereof. At the front of the frame at either side of the longitudinal median line are disposed two sets C of vertical engines D, very suitably of the gasoline-motor type. These engines are supported by the frame and overlie two longitudinal crank-shafts E, which are journaled in front cross-piece F. Each crank-shaft is provided advantageously at its rear end with a fly-wheel H.

I are a pair of intermediate shafts located in rear of and in alignment with the crank-shafts and suitably journaled in cross-pieces K and L of the frame. Also journaled in these cross-pieces is the forward section M of the driving-shaft N, which extends rearward in the plane of the longitudinal center of the machine and connects with the axle N' of the drive-wheels. O and P are the casings of ordinary forms of gearing.

The intermediate shafts I are geared to

the drive-shaft between the two adjacent parallel cross-pieces K and L, and the gearing is very simply effected by providing the section M of the drive-shaft with two sprocket-wheels Q and R, the one in rear of the other, and the shafts I each with a sprocket-wheel S, opposed to one of the sprockets Q and R.

The intermediate shafts I are coupled to the crank-shafts by means of cone-clutches T, the male members or cones U being carried by the forward ends of the intermediate shafts and the female members V being carried by the rear ends of the crank-shafts immediately behind the fly-wheel.

It will be understood that the cones are splined to slide longitudinally on the intermediate shafts, and this sliding is effected through levers W, pivoted at one end, as at a, to the frame, intermediately, as at b, to curved sectors e, embracing a circular groove d in each cone, and at their other ends, as at e, to links X. These last are shown extending upward and rearward to crank-arms f, borne by spaced rock-sleeves g, which are mounted on a transverse rod h. Each of these sleeves carries a rigid upstanding foot-lever Y conveniently located for the operator.

Mounted on the rod h, intermediate the sleeves g, is a rock-sleeve k, which carries a foot-lever Z, which is disposed to rock its sleeve in the opposite direction from that in which pressure of the chauffeur's foot rocks the sleeves g. A transverse pin or rod m, carried by the foot-lever Z, is disposed to bear against the front of the shanks of the levers Y, so that both of the foot-levers Y may be thrown rearward by depressing the lever Z.

It will be understood that either set of engines may be thrown in by pressing the appropriate lever Y forward with the foot and that pressure upon both levers will throw in both sets. The forward movement of either or both of the levers Y necessarily shifts the lever Z, so that subsequent pressure upon this lever will throw out either set or both, as the case may be.

What is claimed as new is—

1. In a motor-vehicle, the combination with a vehicle-frame, of two motors disposed at the front thereof at either side of the longitudinal center, a pair of longitudinal shafts driven directly by said motors, intermediate shafts located in rear of and in axial alignment with said first-named shafts, a driving-shaft disposed centrally and longitudi-

- dinally at the rear of the frame, permanent gear connection between the intermediate shafts and the driving-shaft, and means for throwing either or both of the intermediate shafts into operative connection with the motor-shafts.
2. In a motor-vehicle, the combination with a vehicle-frame, of two motors disposed at the front thereof at either side of the longitudinal center, a pair of longitudinal motor-shafts, intermediate shafts located in rear of and in alignment with said motor-shafts, a central longitudinal driving-shaft at the rear of the frame, gearing between the intermediate shafts and the driving-shaft, means for coupling either or both the intermediate shafts with the motor-shafts, and means for simultaneously uncoupling both intermediate shafts.
- 20 3. In a motor-vehicle, the combination with a vehicle-frame, of two motors disposed at the front thereof at either side of the longitudinal center, a pair of longitudinal motor-shafts, intermediate shafts located in alignment with said motor-shafts, a central longitudinal driving-shaft at the rear of the frame, gearing between the intermediate shafts and the driving-shaft, a clutch between each motor-shaft and the corresponding intermediate shaft, a pair of foot-levers operable independently to throw said clutches into operative position, and a foot-lever depressible to effect the reverse operation of both the other levers.
- 35 4. In a motor-vehicle, the combination with a vehicle-frame, of two motors disposed at the front thereof at either side of the longitudinal center, a pair of longitudinal motor-shafts, intermediate shafts located in alignment with said motor-shafts, a central longitudinal driving-shaft at the rear of the frame, gearing between the intermediate shafts and the driving-shaft, a clutch between each motor-shaft and the corresponding intermediate shaft, a transverse rod a pair of spaced rock-sleeves thereon, each carrying a foot-lever and a crank-arm, a rock-sleeve mounted on the rod intermediate

the other two sleeves and carrying a foot-lever adapted to be depressed reversely from the other two foot-levers and provided with a transverse member designed to engage operatively with said other two levers, and connections between the crank-arms and the clutches.

5. In a motor-vehicle, the combination with a vehicle-frame, of two engines disposed at the front thereof at either side of the longitudinal center, a pair of longitudinal crank-shafts, intermediate shafts located in alignment with said crank-shafts, a central longitudinal driving-shaft located at the rear of the frame and centrally and longitudinally thereof, gearing between the intermediate shafts and the driving-shaft, fly-wheels and female cone-clutch members carried by the rear ends of the crank-shafts, male cone-clutch members slidable on the front ends of the intermediate shafts, and means for throwing either or both male clutch members into engagement with the female members.

6. In a motor-vehicle, the combination with a vehicle-frame provided with cross-pieces, of two engines disposed at the front of the frame at either side of the longitudinal center, a pair of longitudinal crank-shafts journaled in cross-pieces of the frame, intermediate shafts located in alignment with said crank-shafts and journaled in adjacent cross-pieces of the frame, a driving-shaft disposed centrally and longitudinally at the rear of the frame and having a forward section journaled in said adjacent cross-pieces, gearing connecting the intermediate shafts and driving-shafts between said cross-pieces, and means for coupling the intermediate shafts and the crank-shafts.

In testimony whereof I have signed my name to this specification in the presence of two subscribing witnesses.

HOWARD O. CARTER.
